Term of patent 14 years

(Cl. D44—6)

FIG. 3

FIG. 4

FIG. 2

FIG. 1

FIG. 1 is a perspective view of a canister drawer embodying my new design;

FIG. 2 is a top plan view;

FIG. 3 is a front elevational view; and

FIG. 4 is a side elevational view, partly in section.

The essential feature of the design resides in the particular configuration of the handle in combination with the particular configuration of the recessed area and the cylindrical handle support member.

I claim:

The ornamental design for a canister drawer, substantially as shown and described.
